DYNAMITE BOX

John V. Hammond, Spangler, Pa.

Application February 26, 1940, Serial No. 320,939

2 Claims. (Cl. 224—20)

This invention relates to an improved dynamite box.

One object of the invention is to provide a dynamite box fabricated completely of wood so that no electric current carrying material of any description will be embodied in its construction.

A further object of the invention is to provide a dynamite box having an improved latch for the front closure wall thereof, said latch employing a nonmetallic tensioning means.

A further object of the invention is to provide a device of this character wherein the top and bottom walls are fitted by dove-tail construction so that separation of said walls from the side walls will be effectively prevented.

And a still further object of the invention is to provide a box of this character which will be of simple construction and which will be highly efficient in use.

Other objects of the invention, not specifically mentioned in the foregoing, will become apparent during the course of the following description.

In the accompanying drawing forming a part of my application.

Figure 1 is a perspective view of my improved dynamite box.

Figure 2 is a vertical sectional view on the line 2—2 of Figure 1, looking in the direction indicated by the arrows.

Figure 3 is a vertical sectional view on the line 3—3 of Figure 2.

Figure 4 is a top plan view of the device, the handle employed being partly broken away in order better to show the position of the tensioning means when the latch employed is in operative position for holding the front closure in closed position.

Referring now to the drawing, throughout the views of which like numerals of reference will be seen to designate like parts, the numerals 1 and 2 indicate the side walls of my improved dynamite box. These side walls, as well as all the other parts of the box, are formed of wood or other non-metallic material. The walls 1 and 2 are formed with straight corresponding lower end portions 3 and extended rounded upper end portions 4.

A bottom wall 5 is provided and is located in spaced relation above the corresponding lower ends 3 of the walls 1 and 2. As will be seen by referring particularly to Figures 1 and 3 of the drawing, the bottom wall 5 is formed with dove-tail elements 6 and 7 which are slidably received in slots 8 and 9 which are of dove-tail shape or formation to receive the elements 6 and 7 and

which are located in opposed relation. In forming the box, the bottom is shifted into position with the elements 6 and 7 in their respective slots 8 and 9. Transversely extending grooves 5a and 7a are formed in the bottom wall 5.

Near the corresponding upper end portions of the walls 1 and 2, but beneath the rounded portions 4 thereof, is positioned the top wall 10 of my improved box. The top wall is of greater thickness than the bottom wall 5 and is formed with connecting elements 11 and 12 which, like the elements 6 and 7, are of dove-tail formation. The elements 11 and 12 are slidable in slots 13 and 14 which are shaped to receive said elements and are located in opposed relation to the walls 1 and 2.

Formed in the top wall 10, substantially medially of its width and extending the major portion of its depth, is a dove-tail shaped guide slot 15.

20 The guide slot communicates with the forward edge of the wall 10 and slidably receives a guide element 16 which is formed on the under side of a latch member 17, said latch member being of substantially rectangular shape in cross section and being of a length substantially the same as the depth of the complete dynamite box. As will be seen by referring to Figure 2, the guide element 16 terminates short of the forward end of the latch member 17 a distance equal to the thickness of the front closure 18 presently to be described in more detail.

25 In order normally to urge the latch member 17 forwardly, I provide a rubber band 19. By referring to Figures 1 and 4 of the drawing, it will be seen that the band 19 is stretched so that portions thereof are fitted in slots 20 formed in the front edge of the top wall 10 near the ends thereof. The band 19 is stretched rearwardly in straddling relation to the latch member 17 and has a rear portion engaged in an inclined kerf or notch 21. It will now be understood that the band 19 will normally urge the latch member 17 forwardly so that the front end face of the element 16 will engage the upper inner margin of the front closure 18. In this position, the forward end of the latch member will overhang the upper edge of the front closure 18 for effectively holding said front closure in closed position.

30 The front closure 18 is formed with guides 22 and 23 which are slidable in vertically extending tracks 24 and 25 formed in the walls 1 and 2 near their corresponding forward edges. Formed in the front face of the closure 18 is a finger hold 26 which will permit convenient raising of the closure for exposing the interior of the box,

when the latch member 17 is retracted, for freeing the forward end thereof from the upper edge of said front closure 18. A tongue 18a is formed on the lower end of the front closure 18 and is engageable in the groove 6a, formed in the bottom wall 5, when said front closure is in closed position.

My improved dynamite box is provided with a rear wall 27 which is held in place at its upper end by means of wooden dowels or pins 28 which extend through the rear margin of the top wall. Under no circumstances will nails or other metal fastening devices be employed. Any suitable number of the dowels or pins 28 may be used. The upper end of the rear wall is reinforced by engagement with a shoulder 10a on the lower rear edge of the top wall 10. As shown in Figure 2, the rear wall 27 is formed at its lower end with a tongue 27a which engages in the groove 7a in the bottom wall 5. As will be seen in Figure 4, the rear wall 27 is formed with guides 28a which are slidably engageable in grooves 28b which extend along the side walls for a distance equal to the height of the rear wall. It will now be seen that the rear wall will be effectively held in place without the use of metallic fastenings of any kind.

In order to permit convenient handling of my improved dynamite box, I employ a handle 29 which extends between the side walls 1 and 2 at the curved upper ends 4 thereof.

In use, it is desirable that the entire surface of my improved dynamite box be covered with a coating of paraffin or other protective substance. The box is of rugged construction and will withstand hard usage. Due to the fact that no metal parts of any description are employed in its construction, there will be no danger of the setting off of explosives within the box such as might be caused by electrical discharges.

Attention is directed to the fact that inasmuch as the guide slot 15 is of a shape to closely conform to the shape of the guide element 16, upward displacement of the latch member from the 5 wall 10 will be prevented.

Having thus described the invention, what is claimed is:

1. In a dynamite box having a top wall and a front closure, said top wall having a guide slot 10 of dove-tail shape, said top wall having slots located near the ends of its forward edge, a latch member carried by the top wall and having a guide element of dove-tail formation slidable in the guide slot, said guide element terminating 15 short of the forward end of the guide slot, and a resilient band carried in the slots in the top wall and engageable with the latch member for normally urging the latch member forwardly so that the forward end of the guide element will confront the upper inner margin of the front closure and the forward end of the latch member will overhang the upper edge of said front closure for preventing upward displacement of the front closure, said dove-tail shaped guide slot co-operating with the dove-tail shaped element for preventing upward displacement of the latch member from the top wall.

2. A dynamite box having a top wall formed with a slot, a front closure for the box, a latch member having a guide element slidable in the slot, said latch member having a notch and said top wall having spaced slots, and a resilient band extending between the top wall and the latch member and being engaged in the notch 30 and the slots and normally urging the latch member into a position with its forward end portion overhanging the front closure and latching said front closure in place.
